GUN TURRET

Clayton G. Fogle, Williamsport, Pa.

Application September 15, 1941, Serial No. 410,938

6 Claims.

(CL. 89—37)

My invention relates to gun mounts, and has among its objects and advantages the provision of an improved turret particularly adapted to installation of guns in tanks and the like.

In the accompanying drawings:

Figure 1 is a front elevational view of a gun turret in accordance with my invention;

Figure 2 is a rear elevational view;

Figure 3 is a sectional view taken along the line 3—3 of Figure 1;

Figure 4 is a top plan view of the turret structure with the gun mounting facilities removed;

Figure 5 is a sectional view along the line 5—5 of Figure 4; and

Figure 6 is an enlarged sectional view along the line 6—6 of Figure 3.

In the embodiment selected for illustration, I make use of a base 10 which may be fixedly secured inside a tank as indicated in my application for patent on airplane tank filed of even date herewith. A flange 12 is provided on the base through the medium of which the base may be bolted to a suitable support.

On the base 10 is secured an upright post or screw 14 having threaded connection with a sleeve 16, the upper end of which is provided with an internal flange 18 and an annular end flange 20. Inside the flange 20 is rotatably mounted a short shaft 22 having a pin 24 rotatably guided by the internal flange 18.

The shaft 22 is provided with a horizontal floor 26 at its upper end having an annular depending flange 28 about its perimeter. A groove 30 is formed in the upper end of the shaft 22 to provide clearance for a projection 32 depending from a base plate 34 of a gun supporting bracket 36. The plate 34 rests on the floor 26 and is slidably guided thereon by L flanges 38 fixed to the floor 26.

Threadedly connected with the projection 32 is a screw 40 having an end 42 rotatably journaled in a body 44 formed on the flange 28 and its other end rotatably supported in a bore 46 in the flange. A hand wheel 48 is keyed to the screw 40 to facilitate rotation thereof, and the screw is held against relative axial movement so that rotation of the screw imparts sliding movement to the bracket 36.

Two upstanding plates 50 are fixed to the base plate 34 and are provided with coaxial bores 52 for rotatably supporting a shaft 54 on each end of which is mounted a rocker arm 56. Each rocker arm comprises a first section 58 fixed to a second section 60 by a rivet 62. One first section 58 is keyed at 64 to the shaft 54 and the other

first section 58 is keyed at 66 to a worm gear 68 keyed at 70 to the shaft 54.

A worm 72 meshes with the worm gear 68 and is rotatably journaled in ears 74 on one of the plates 50. The worm 72 is rotated through the medium of a hand wheel 76.

Between the second sections 60 is mounted a gun 78 having a flat-sided body 80 fitting snugly between the sections. Each section is provided with a slot 82 for the reception of a screw 84 threaded into the body 80. In Figure 3 the second sections 60 are arranged at right angles to the first sections 58, and the gun body 80 is loosely positioned between the second sections.

15 A shield 86 is bolted at 88 to the flange 28, this shield curving in conformity with the flange 28 and extending slightly more than one hundred and eighty degrees about its forward perimeter. Parallel and vertical L flanges 90 are welded to the shield 86 for slidably guiding a safety slide 92 having an opening 94 for accommodating the gun barrel 86 and a slot 98 accommodating the telescopic sight 100 of the gun. The safety slide 92 may be adjusted vertically and the gun 78 20 may pivot about the axes of the screws 84, with the rocker arm structure 56 adjustable for height through rotation thereof about the axis of the shaft 54.

25 When the gun barrel is pivoted downwardly at a predetermined angle, the portion of a slot 102 uncovered by the safety slide is closed by a shutter 104 slidably in L flanges 106 welded to the shield 86 and arranged at right angles to the L flanges 90. The slot 102 is of considerable length so as to permit the gun barrel to be pivoted in a vertical plane throughout a considerable degree.

30 The shaft 22 is rotatably supported in the flanges 18 and 20 and is provided with a circumferential groove 108 for the reception of key pins 110 on screws 112 threaded into the flange 20. Thus the shaft 22 is keyed against accidental axial movement but may be rotated to facilitate adjustment of the gun about a vertical axis. The 35 sleeve 16 may be adjusted vertically through rotation about the screw 14, the sleeve being provided with a hand wheel 114 to facilitate rotation thereof.

36 While the shield 86 is curved, the shutter 104 is also curved so as to slide easily in the L flanges 106, a knob 116 being attached to the shutter to aid in shifting the shutter from side to side. The front wall structure of the tank in which the gun 40 turret is installed must, of course, have a curvature conforming to the shape of the shield 86,

and the front wall must be provided with an opening of such size as to permit desirable adjustment of the gun in vertical and horizontal directions, with the shield covering the opening in the tank wall in all firing positions of the gun. The gun 78 may be pivoted about a vertical axis, since the shaft 22 is rotatably supported in the flange 20. The gun may be conveniently adjusted vertically through adjustment of the sleeve 16 on the post 14.

The gun may also be adjusted horizontally for convenient location of the gun with respect to its supporting structure, which adjustment is attained through rotation of the handwheel 48. Minor vertical adjustments of the gun is attained through manipulation of the hand wheel 76, this wheel being located in close proximity to the wheel 48, so that both wheels are easily accessible. The slots 82 permit vertical manipulation of the gun with respect to the rocker arms 56, which movement aids in manipulation of the gun. The safety slide 92 shifts easily relatively to the shield 86 so as to respond to vertical movement of the gun barrel. When the safety slide 92 is moved a considerable distance downwardly 25 it uncovers the slots 102 at the upper part of the shield 86, but the shutter 104 may be shifted horizontally to afford coverage for the uncovered extent of the slot.

Without further elaboration, the foregoing will so fully illustrate my invention, that others may, by applying current knowledge, readily adapt the same for use under various conditions of service.

I claim:

1. In a device of the type described, a supporting means, a gun supporting bracket mounted for horizontal sliding movement on said supporting means, a screw mounted on said supporting means and operatively connected with said bracket to impart adjustment thereto through rotation of the screw, fixedly related rocker arms mounted on said bracket for rotation about a horizontal axis, gears means operatively connected with said rocker arms to impart rotation thereto, a gun

positioned between said rocker arms and having a barrel, said rocker arms having slots, pin means attached to said gun and extending loosely through said slots to movably connect the gun

5 with the rocker arms, a shield attached to said supporting means and having a vertical slot for loosely receiving said barrel, a safety slide mounted for vertical sliding movement on said shield and across said vertical slot, said safety slide having an opening for loosely receiving said barrel, and a shutter slidably mounted on said shield for movement transversely of said safety slide and coacting therewith to cover said vertical slot.

10 2. The invention described in claim 1 wherein said supporting means includes a horizontal floor, and flanges fixed to said floor for slidably guiding said bracket.

15 3. The invention described in claim 1 wherein said supporting means includes a horizontal floor, flanges fixed to said floor for slidably guiding said bracket, said floor having a slot, and a lug 20 fixed to said bracket and threadedly connected with said screw.

25 4. The invention described in claim 1 wherein said supporting means includes an annular flange, means connecting said shield with said annular flange, and means supporting said supporting means for rotation about a vertical axis.

30 5. The invention described in claim 1 wherein said bracket includes two spaced plates, said rocker arms overlapping portions of said plates, and a shaft rotatably journaled in said plates and fixedly related to said rocker arms, said gear means including a worm gear fixed to said shaft, and a worm rotatably mounted on one of said plates and meshing with said worm gear.

35 6. The invention described in claim 1 wherein said rocker arms each comprises two sections fixedly connected one with the other in the form of an elbow, and in which said first mentioned slots are elongated transversely of one section in each rocker arm.

CLAYTON G. FOGLE.
